(57) **CLAIM**

(22) Filed: **Mar. 28, 2001**

The ornamental design for a casing of a device for the measurement of distances, as shown and described.

(30) **Foreign Application Priority Data**

DESCRIPTION

Sep. 28, 2000 (XH) DM/053 958

FIG. 1 is an oblique view from the top, right, rear of the casing of a device for the measurement of distances showing our new design;

(51) LOC (7) Cl. **10-04**

FIG. 2 is a top view thereof;

(52) U.S. Cl. **D10/70**

FIG. 3 is a right side view thereof;

(58) Field of Search D10/70; 702/150,

FIG. 4 is a left side view thereof;

702/208, 158, 5; 33/261, 285, 286, 700-719;

FIG. 5 is a rear view thereof;

356/138, 139.03, 141.3, 142, 5.12, 4.05,

FIG. 6 is a front view thereof; and,

5.07, 5.15, 28.5, 5.09

FIG. 7 is a bottom view thereof.
